United States Patent Office.

WILLIAM J. THOMPSON, OF SPRINGFIELD, MISSOURI.

Letters Patent No. 98,125, dated December 21, 1869.

IMPROVEMENT IN WATER-WHEELS.

The Schedule referred to in these Letters Patent and making part of the same.

To all whom it may concern:

Be it known that I, WILLIAM J. THOMPSON, of Springfield, in the county of Greene, and State of Missouri, have invented a new and useful Improvement in Water-Wheels; and I do hereby declare that the following is a full, clear, and exact description thereof, which will enable others skilled in the art to make and use the same, reference being had to the accompanying drawings, forming part of this specification.

This invention relates to improvements in that class of horizontally-running wheels which receives the water from above or below, upon curved buckets, taking the water at one side and discharging it at the other; and

It consists of an improved arrangement of vertically-oscillating gates, which, when open, form chutes for the water.

It also consists of improved means for working the gates.

Figure 1 represents a vertical section of the said wheel, taken on the line *x x* of fig. 1, and

Figure 2 represents a plan view of the same.

Similar letters of reference indicate corresponding parts.

A is the shell of the wheel, and *B*, the buckets, projecting radially from the vertical face of the shell, and in curved lines from the top of the said face to the bottom. In this example they are represented as receiving the water at the top and discharging it at the bottom.

C is the exterior fixed rim, and *D* the curb, which prevents the water from passing down through the centre of the wheel.

This curb has a vertical face, *E*, rising up on the line of the inner rim *F* of the wheel *A*, considerably above the top of the same, and the exterior rim *C* rises nearly as high as the said vertical face of the curb.

G represents the gates, which consist of curved plates, arranged on central pivots, between the rim *C*

and the rim *E* of the shell *D*, so as to swing in vertical planes in opening and closing.

In closing, the upper end of each gate shuts down against the next preceding it, so as to lap thereon for a considerable distance, from the lower end toward the axial bolt, the curvatures of each being pre-arranged to fit in this way.

The upper ends of all the buckets are arranged between two pins, *a*, for each bucket projecting inwardly from a rim, *I*, resting on the top of the rim *C* of the case, and which is oscillated by toothed gearing, or other suitable devices for opening and closing the buckets by the action of the pins thereon, in sliding over the ends of the buckets.

These buckets are hung at the centre, so as to be balanced by the equal action of the water on both sides, when open.

These gates take the place of the fixed chutes commonly used, and save the expense of the same. Moreover, they are attached to the wheel in the construction of the same, and all completed in the shop, so that in setting the wheel up, the expense of arranging the gates and chutes is avoided.

The gates are so curved on the edges as to fit snugly the curvatures of the rims *C* and *E*, when closed.

Having thus described my invention,

I claim as new, and desire to secure by Letters Patent—

1. The combination, with a wheel arranged to receive the water as described, of the gates *G*, pivoted between the rims *C* and *E*, and arranged for operation substantially as specified.

2. The combination, with the gates *G* and rim *C*, of the movable rim *I* and pins *a*, when arranged for opening and closing the said gates, substantially as specified.

WM. J. THOMPSON.
